(57) **CLAIM**

The ornamental design for a terminal crimping pliers, as shown and described.

DESCRIPTION

FIG. 1 is a perspective view of a terminal crimping pliers showing my new design;

FIG. 2 is a front end view thereof;

FIG. 3 is a rear end view thereof;

FIG. 4 is a left side view thereof;

FIG. 5 is a right side view thereof;

FIG. 6 is a top plan view thereof; and,

FIG. 7 is a bottom plan view thereof.

The broken lines in the drawings are for the purpose of illustrating unclaimed portions of the terminal crimping pliers and form no part of the claimed design.
